AIR DIFFUSING MEANS

Augustus C. Durdin, Jr., Lincolnwood, Ill., assignor to Chicago Pump Company, Chicago, Ill., a corporation of Illinois

Application July 13, 1938, Serial No. 219,099

5 Claims. (Cl. 261—124)

This invention relates to air diffusing means of that character intended principally for use in the aerating tanks of sewage treatment plants, and has reference more particularly to that type of diffusing means which employ porous, hollow diffusers connected with a header for supplying air to the contents of the tank in which the diffusing means is employed.

Generally speaking, air under pressure is forced through a header which is disposed adjacent the bottom of the tank adjacent one wall thereof, to which header a great multiplicity of diffusers are attached and through the pores of which the air is forced into the surrounding liquid. Diffusers are composed of porous material and occasionally one breaks and when this occurs with the diffusers heretofore in use, great quantities of air are discharged from the broken diffuser thereby reducing the pressure in the header so that the diffusers do not supply the required amount of diffused air throughout the tank.

One of the objects of the present invention is to provide means whereby when a diffuser breaks, the amount of air escaping therefrom is insignificant as compared with that escaping when the ordinary diffuser becomes broken. The pressure in the header is not materially reduced and, therefore, the proper functioning of the other diffusers is not interfered with. Furthermore, in case several diffusers become broken, the deficiency in pressure may be readily made up to the required pressure.

Headers are usually of great length, sometimes extending from 100 to 500 feet in length, and the desideratum is to have them supported in a level condition, and one of the objects of the present invention is to provide supports for the headers having leveling means whereby the headers may be supported in a level condition. Another object is to provide means for anchoring the supports permanently to the bottom of the tank.

With these and other objects and advantages in view, this invention consists in the several novel features hereinafter more fully set forth and claimed.

The invention is clearly illustrated in the drawings accompanying this specification in which:

Fig. 1 is a vertical, longitudinal section taken through an aerating tank, partly broken away, and illustrating one embodiment of the invention applied thereto.

Fig. 2 is an enlarged view partly in side elevation and partly in vertical longitudinal section through a header and two diffusers, one partly

broken away, the line of section being indicated at 2—2 in Fig. 1.

Fig. 3 is an end view of a diffuser looking in the direction of the arrow 3 in Fig. 2.

Fig. 4 is an end elevation of the diffuser looking in the direction of the arrow 4 in Fig. 2.

Fig. 5 is a vertical cross section taken on the line 5—5 of Fig. 2.

Fig. 6 is a vertical cross section taken on the line 6—6 of Fig. 1.

Fig. 7 is an enlarged view partly in elevation and partly in cross section of one of the supports or standards and a header, the line of section being indicated at 7—7 in Fig. 1.

Fig. 8 is an enlarged, fragmental, vertical, longitudinal section taken through a header and a modified form of the diffuser.

Fig. 9 is an end elevation of the diffuser seen in Fig. 8 looking in the direction of the arrow 9.

Fig. 10 is an end elevation of a second modified form of diffuser.

Referring to said drawings and first to Figs. 1 to 7 inclusive, the reference characters 10 designate a series of aerating tanks usually composed of concrete and comprising a common bottom 11 from which rise longitudinally extending walls or partitions 12 which separate the tanks from each other. Fillets 13 may be provided at the corners of the tanks (see Fig. 5) to facilitate circulation of the tank contents therein. End walls 14, 15 are provided at the ends of the tanks and an influent conduit or gutter 16 is provided at the top of the end wall 14, and an effluent conduit 17 is provided at the top of the other end wall 15, which conduit is provided with a weir 18 over which the tank contents overflows into the effluent channel or gutter. At one end of the tanks is a passageway 19 formed between the end wall 14 and an outside wall 20.

Leading from a suitable air pump or compressor (not shown) is a main header 21 which extends through the passageway 19, and from said header 21 lead diffuser headers 22 which pass through the end walls 14 of the tanks adjacent the bottoms thereof and extend along the lengths of the tanks adjacent one of the walls 12 thereof. Standards or other supports 23 are provided along the length of the diffuser headers for supporting them in a level condition. To maintain a substantially even pressure throughout the lengths of the diffuser headers, they are formed in sections stepped down in diameter from the main header to the other end of the tanks. Flexible couplings 24 are provided between the adjacent

header sections to permit of slight misalignment thereof.

5 A trap 25 is interposed in each diffuser header in the passageway 19, which trap collects foreign particles, oil and water that may find its way to the diffuser headers. A blow-off pipe 26 leads from each trap 25 and is provided with a valve 27 whereby when the valve is opened, the accumulated foreign matter may be blown out of the trap.

10 Each diffuser header is drilled and tapped at a great multiplicity of closely spaced places along its length on both sides to provide discharge openings into which are screwed the adapters or connections of the diffusers 28, which project horizontally from the header on both sides thereof in parallel relation to each other.

15 The diffusers are of similar construction and a description of one will suffice for all.

20 Referring to Figs. 2 to 5 inclusive, the diffuser will be seen to consist of a hollow body portion 29 desirably formed of carbon or other suitable porous material and in its preferred form the body portion is composed of an upper section 30 which is porous and a lower section 31 which is not required to be porous, the two sections being cemented or otherwise suitably fastened together. This shape of diffuser body is of the type known as the "tear drop" type. One end 30 of the hollow body is closed by a head 32 and upon the other end is an adapter 33 which is provided with a hexagonal or other noncircular part 34 for the reception of a wrench and a threaded stem 35. Desirably, gaskets 36 are interposed between the body 29 and the head 32 and adapter 33 to make tight joints therebetween, and a rod 37 threadedly secured in the adapter 33 and provided with a nut 38 on its other end is employed for rigidly securing together the parts 40 of the diffuser. A restricted duct 39 extends through the adapter from the hollow of the diffuser body to the end of the stem 35 and provides a restricted communication between the interior of the header and the hollow of the diffuser.

45 Ordinarily, adapters for diffusers are provided with relatively large passages therethrough for connecting the interior of the header with the hollow of the diffuser, the result being that whenever a header becomes broken, great volumes of air under pressure are discharged into the liquid, thereby materially lowering the pressure in the header and preventing the other diffusers from functioning properly. With the use of a restricted duct between the interior of the header and the hollow of the diffuser, then in case a diffuser becomes broken the air can only escape in relatively small quantities from the header through the restricted orifice, with the result that the pressure in the header is not reduced materially, and, consequently, the functioning of the other diffusers is not materially interfered with.

50 In the operation of the diffusing means, air under pressure is forced through the headers to 65 and through the restricted ducts into the hollows of the diffusers, from which the air is forced through the porous walls thereof and escapes in minute particles into the liquid surrounding the diffusers, whereupon innumerable small air bubbles are formed and the air is absorbed by the liquid. Furthermore, the liquid above the diffusers is lightened and thereby rises, causing a circulation of the liquid as indicated generally by the arrows in Fig. 6.

70 75 One of the standards for supporting the head-

ers is illustrated in detail in Fig. 7 and comprises a hollow conical base 40 having one or more filler openings 41 in its side wall and formed at its upper end with a threaded boss 42 in which is threadedly mounted a post 43 which is provided 5 upon its upper end with a saddle 44 upon which the header rests. A stirrup 45 having threaded ends passing through the end portions of the saddle and provided with nuts 46 provide means for clamping the header down upon the saddle. 10 In assembling the header and standards, the latter are placed underneath the header and the posts are adjusted vertically so as to hold the header in level condition. During the assembling of the parts the standards may be shifted about 15 to accommodate the header sections in case of any misalignment thereof and, after the parts have been placed in position, concrete 47 is poured through the openings 41 in the bases in order to weight and to fasten them to the bottom 20 of the tank.

25 In the modified form of the invention illustrated in Figs. 8 and 9, the duct 39^a of the adapter 33^a may be of greater diameter than that illustrated in Fig. 2 and at its inlet end it is provided with a valve 48 desirably of the flap valve type hinged to the stem 35^a at 49. In all other respects, the diffuser may be constructed in accordance with one illustrated in Fig. 2. In this case air under pressure flows past the flap valve 30 into the duct 39^a and passes into the hollow of the diffuser body. In case the diffuser becomes broken, the rush of air from the header will cause the valve 48 to close or partially close, thereby entirely shutting off or at least restricting the 35 flow of air through the duct 39^a to a considerable extent so that only a minimum amount of air may be discharged from the header through the broken diffuser.

40 In Fig. 10 is illustrated a cylindrical form of diffuser 28^b which is provided with an adapter 33^b which may be of the restricted duct type illustrated in Fig. 2 or the valve type illustrated in Fig. 8. The cylindrical wall of the body of the diffuser seen in Fig. 10 is composed of porous material as in the other forms, and in case it becomes broken, only a minimum amount of air may escape from the header at the broken diffuser.

45 It is to be understood that the term "header" 50 which has been used throughout the specification and claims is intended to include any form of air conduit through which air is supplied to the diffusers. Furthermore, the supports for the headers may be carried from above or below the headers.

55 I claim as new and desire to secure by Letters Patent:

1. Air diffusing means, comprising in combination a header through which air is supplied under pressure, a horizontal porous diffuser tube, provided on one end with an adapter threadedly secured in said header and having a single restricted duct leading from the interior of the header to the hollow of the diffuser, whereby, whenever the diffuser is broken, a restricted amount of air is permitted to escape through the duct.

with that of the hollow of the diffuser, whereby a restricted amount of air is permitted to escape from said duct whenever the diffuser is broken.

- 5 3. Air diffusing means for diffusing air into a body of liquid, comprising in combination a header through which air is supplied under pressure, and a horizontal porous diffuser tube closed at one end and having a threaded adapter secured thereto at its other end and threadedly secured to 10 said header, there being a single restricted air passage through the adapter between the interior of the header and the hollow of the diffuser, through which air is forced into the hollow of the diffuser, and out through the pores thereof into 15 a body of liquid surrounding the diffuser, the cross-sectional area of the restricted air passage being relatively small as compared with that of the hollow of the diffuser, whereby, whenever the 20 diffuser is broken, a restricted amount of air is permitted to escape from the broken diffuser.
4. Air diffusing means for diffusing air into a body of liquid comprising in combination a header having a multiplicity of closely spaced discharge openings in both of its sides, a multiplicity of diffusers extending horizontally from said 25

header, in parallel relationship from both sides thereof, each diffuser having a porous, hollow, elongated tubular body, closed at its outer end and having an adapter secured to its other end and forming a supporting connection between the diffuser tube and the header, there being a single restricted air duct through the adapter extending between the header and diffuser tube, whereby, whenever any diffuser is broken, a restricted amount of air is permitted to escape from the 10 broken diffuser without materially reducing the pressure in the header.

5. The combination of a header through which air is forced under pressure, a horizontal porous diffuser tube closed at one end and means secured to the other end forming a supporting connection between the diffuser tube and header, said means having a single restricted duct therein leading from the header to the diffuser tube whereby to restrict the escape of air from the header, at the place where the diffuser tube is secured thereto, whenever the diffuser tube 15 20 breaks.

AUGUSTUS C. DURDIN, JR. 25
